UNITED STATES PATENT OFFICE.

GUSTAF DALÉN, OF STOCKHOLM, SWEDEN, ASSIGNOR TO SVENSKA AKTIEBOLAGET
GASACCUMULATOR, OF STOCKHOLM, SWEDEN.

RAILWAY SIGNALING SYSTEM.

1,153,840.

Specification of Letters Patent. Patented Sept. 14, 1915.

Application filed July 1, 1911. Serial No. 636,440.

To all whom it may concern:

Be it known that I, GUSTAF DALÉN, a subject of the King of Sweden, residing at No. 104 Odengaten, Stockholm, Sweden, have invented new and useful Improvements 5 in Railway Signaling Systems, of which the following is a specification.

This invention relates to signal devices for railroads, and has for its object to make 10 possible a greater variety of signals than are used at present, and to make the signals more distinct for the locomotive engineers.

The purpose of this invention is to substitute flash signals for the present styles of 15 illuminated signals, or to use the former in combinations with the latter. As these flash signals may be white or colored, as desired, it may be readily understood that a multitude of signal combinations can be obtained.

Used singly or in combinations, they are 20 more easily observed and more quickly read off than is possible with signals of the old pattern. The source of light used can be either gas or electricity. Lamps not necessary 25 to be seen during certain periods may be temporarily screened off or extinguished automatically and all signals can be changed with greatest facility.

In the accompanying drawings, Figures 30 1, 2, 3 and 4 are diagrammatic views. Fig. 5 is a front view of a signaling device embodying the invention. Fig. 6 is a side view of the device shown in Fig. 5.

To illustrate this invention, reference is 35 made to the diagrammatic views shown in Figs. 1-4. A number of signal devices in current use are shown, also possibilities of new combinations. Fig. 1 shows a group in which each semaphore is provided with a 40 mast 1, 2, 3, an arm 4, 5, 6 and a lantern 7, 8, 9. The arms are intended for daylight signals and the lanterns for signaling at night. Lantern 8 (in two circles) is for 45 intermittent flashes and side lanterns 7 and 9 for constant lights. This figure shows a signal combination suitable for a railroad junction, where three lines meet (one main line in the center and a branch on either side). In a case like this one signal is of 50 greater importance than the others and should be more distinct. Lantern 8 shows a signal with intermittent flashes, which must and can be seen at great distance, while lanterns 7 and 9 give stationary lights or 55 are dark or screened off. The intermittent

light may be white or colored, as desired, or required by circumstances. If any of the branch lines desires to show a very important signal, the intermittent flash signal may be placed on the semaphore designating the 60 same. Two or more of the lanterns in the group may, of course, be arranged for intermittent lights. A similar arrangement of stationary lights in combination with one or more intermittent lanterns may also be used 65 on signal bridges. Figs. 2-4 show different signals placed under each other in a group. 1 shows the semaphore mast, 4, 5, 6 the semaphore arms and 7, 8, 9 the signal lanterns. 8 represents a lantern with intermittent light, white or colored, while lanterns 7 and 9 give stationary lights, white or colored. According to the signal system in use, the flash signal in this group may be used in combination with the other lights 70 in the same group, each combination having a meaning of its own. The flash may be placed at the bottom (Fig. 2), on top (Fig. 3), or in the center (Fig. 4). By varying the number of signal lanterns in each group, 75 as well as their relative positions, the presence in the group of one or more intermittent flash lanterns will allow a far greater number of signal combinations than would be possible if only stationary lights were 80 burning.

Figs. 5 and 6 show in two side views the methods to be followed when, in placing a signal, lanterns may be lighted or darkened 90 automatically, as required. Gas is the illuminating factor. 1 shows the semaphore mast, 4 the upper semaphore arm, and 5 the lower semaphore arm. These arms can be turned in the usual manner around axles 10, 11, and may be provided with counter weights 12, 95 13. 7 is the lantern associated with arm 4, which is supposed to give a stationary light, 8 is the lantern associated with arm 5, which may be considered as giving an intermittent light. This lantern (8) is connected with 100 a gas pipe, in which is inserted a supply regulator 15, and a pressure regulator 16, and is connected to a tank containing gas under pressure, thus, if desired, acetylene 105 gas may be used. The lantern is provided with a burner, a lighting pipe, and an automatic valve, which at certain intervals opens and closes the gas supply to the burner. As such apparatus are well known and extensively 110 used for marine illumination on light-

houses or otherwise, and as their construction is not the main subject at issue in this invention, a special drawing of this lantern is not considered necessary. 18, 19 show the 5 differently colored glasses of the semaphore arm 4, with screens, and 20, 21 the differently colored glasses of semaphore arm 5, with screens. By means of suitable mechanism, as, for example, an arm 22, and a link 10 23, the semaphore arm 4 is connected with the regulator 15 in such a way that the regulator is opened or closed when arm 4 is put in position for a certain signal. By this 15 an advantage is gained in that the consumption of gas in lantern 8 is considerably reduced by automatic closing of the flow of gas when not needed. When the arm 4 moves to its other position the lantern 8 will again be lighted to throw intermittent 20 light. This operation is performed by opening regulator 15. Of course the arm 5 can, if desired, be connected with regulator 15 for lighting or extinguishing lantern 8. If the signal lanterns are furnished 25 with electric lights the arrangements for their automatic lighting or darkening may be considerably simplified. The up and down movements of the semaphore arms will open and close the electric currents. 30 This arrangement should be easily understood without special drawing. What has been said in regard to semaphores, is equally true of every other signaling device, provided it is fitted with rotatable disks or 35 arms, for showing signals by daylight and with lanterns by night.

Having described the invention, what I claim is as follows:

1. In railway signaling apparatus, in 40 combination, a support, an automatically operating flash-light lantern positioned upon the support, a source of supply for said lantern, means for connecting the lantern with the source, a semaphore movably mounted upon the support, and means operatively associated with the semaphore for controlling the connection between source and lantern.
2. In railway signaling apparatus, in 50 combination, a semaphore support provided with a pair of semaphores mounted to be arranged in the different positions in order to have different interpretations, a constantly burning gas lantern mounted on the 55 said support and controlled by one of said semaphores, and an automatically operating gas flashlight lantern mounted on the support and being controlled by the other of said semaphores.

Copies of this patent may be obtained for five cents each, by addressing the "Commissioner of Patents, Washington, D. C."

3. In railway signaling apparatus, in 60 combination, a support, a plurality of semaphores mounted movably upon the support and adapted to be arranged in different positions to have different interpretations, a constantly illuminated lantern arranged upon 65 the support and associated with one of said semaphores, and an automatically operating flash-light lantern mounted upon the support and controlled by one of the semaphores.

4. In railway signaling apparatus, in combination, a support, a constantly illuminated lantern positioned upon the support, a semaphore provided upon the support, an automatically operating flash-light lantern 75 mounted upon the support, a source of supply for the last mentioned lantern, means for connecting the said lantern with the source, and means operatively associated with the said semaphore for controlling the 80 connection between source and lantern.

5. In railway signaling apparatus, in combination, a support, an automatically operating flash-light lantern mounted upon the support, a movable semaphore provided 85 upon the support and associated with the said lantern, a transparent screen carried by the said semaphore and adapted to intercept the light emitted from the lantern when the former occupies one of its operative positions, a constantly illuminated lantern positioned upon the support, a second semaphore movably mounted upon the support and associated with the second lantern, and a transparent screen provided upon 90 the last mentioned semaphore and adapted to intercept the light emitted from the second lantern when the corresponding semaphore occupies one of its operative positions, the said screens being of different colors. 95

6. In railway signaling apparatus, in combination, a support, an automatically operating gas flash light lantern, mounted on the support, a conduit leading to said lantern from a gas receiver, mounted on the 105 mast, a valve in said conduit, and a semaphore, mounted to oscillate on the support, said semaphore being operatively connected to said valve, whereby movement of said semaphore will actuate said valve to open or 110 close said conduit.

In testimony whereof I have signed my name to this specification in the presence of two subscribing witnesses.

GUSTAF DALEN.
